UNITED STATES PATENT OFFICE.

CHARLES E. FULLER, OF LIMA, OHIO.

DESIGN FOR A CHARM.

Application filed July 26, 1922. Serial No. 3,200. Term of patent 7 years.

To all whom it may concern:

Be it known that I, CHARLES E. FULLER, a citizen of the United States of America, residing at Lima, in the county of Allen and State of Ohio, have invented a new, original, and ornamental Design for a Charm, of which the following is a specification, reference being had to the accompanying drawings, forming a part hereof.

I claim:—

The ornamental design for a charm as shown.

CHAS. E. FULLER.

In the presence of—

MAE SHAFFER,
CLEMENT OHLER.
